UNITED STATES PATENT OFFICE

2,689,726

CLOSURE-OPERATOR

Frederick A. Purdy, Scarsdale, N. Y.

Application May 11, 1951, Serial No. 225,751

7 Claims. (Cl. 268—35)

1

This invention relates to closure-operators, and has particular reference to devices for opening, closing, and controlling the operation of, doors of garages, and of similar building-structures.

Objects of the invention are economy in manufacture and in installation, simplicity in design, and dependability in use. Other objects will become apparent in the development of the description.

The instant mechanism is an improvement over the devices disclosed in my prior Patents 2,062,015, issued November 24, 1936, and 2,127,376, issued August 16, 1938, and is an improvement upon or an alternative to the devices described in my pending applications, Serial Numbers 139,081 and 139,082, filed January 17, 1950.

Drawings

A preferred form of the invention is illustrated in the accompanying drawings in which

Figure 1 is a view in perspective of a tire-contacted air-pump;

Figure 2 is a top view and Figure 3 a side view of the rearward end of the overhead mechanism with parts in position as prior to an opening of the doors;

Figure 2-a is a top view and Figure 3-a a side view of the forward end of the overhead mechanism with parts in position as after an automatic opening of the doors;

Figure 4 is an end view in line 4—4 of Figure 3 showing certain features of novelty in this invention;

Figure 5 is a side view of an alternative air-actuator applying to an electric switch; and

Figure 6 is a diagrammatic view illustrating the winding of the door closing cable.

General outline

The door-operator here described has the general appearance of that in my Patent 2,127,376 and those in my co-pending applications, Serial Numbers 139,081 and 139,082.

The relation to the design in general of improvements in this application is shown by the inclusion in Figures 2, 2-a, 3, 3-a, and 4, of contiguous parts that appear in the co-pending applications. Any such contiguous parts identified in drawings of this application are identified by characters of reference the same as used in the co-pending applications. Functions described in the co-pending applications are not gone into here in detail. Superficially it may be noted that the design here shown, as in the

2

co-pending applications, has its door-operating mechanism located overhead in a frame of channel-form 40, supporting by brackets 130 and 131 a track 45 upon which slide runners 48 and 50, with arms 27 extending to the doors from runner 48, and cables 100 and 102 running over respective sheave-wheels 85 and 84 to sheave-wheels on a weight-bracket at the garage-wall supporting two motive weights, an opening-weight and a closing-weight. Instead of setting off means shown in the co-pending applications, a road-wheel contact-unit is used which corresponds to but does not resemble that in my Patent 2,127,376.

As used in reference to any part of the overhead mechanism, the word "forward" means in the direction of the lintel-bracket 94, and the word "rearward" means in the direction of the actuator bracket 232.

It may be observed that in my co-pending application Serial No. 139,082 the single air-cushion acting two ways is located at the rearward end of the frame, while in this application it is located at the forward end.

Tire-contact air-pump and connections

The tire-contact air-pump is imbedded in the driveway that approaches the doorway of the garage, as a means of transmitting to the overhead mechanism an impulse that sets off the door-operator. This consists essentially of a cylinder 13 of pliant material, such as rubber, located across the path of the road-wheels on one side of the car, connected to a pipe 110 that communicates into the garage.

In my preferable design cylinder 13 is closed air tight at both ends by plugs of rubber cemented in, one plug 15 having a hole into which is cemented air-tight the pipe 110 of rust resistant material. The cylinder 13 is fastened at either end by pipe straps 12-b to a base 4 of wood. A protective top 10 is held by metal strips 12-a on either side, fastened into the base 4 by screws 12-c. This protective top is made of rubber and fabric to a stiffness that allows of only a partial and ineffective depression by foot while allowing of full effective depression by the car wheel. Base 4 is imbedded by concrete in the driveway, the concrete coming up to a level somewhat below the middle line of the cylinder 13 so that the top 10 forms a half round convexity above the level of the driveway.

Within the garage a flexible tubing 109 is cemented into the pipe 110 this tubing extending

upward and across to the overhead mechanism and to the rearward end of that where it appears in Figures 2 and 3.

The air-actuator

The actuator, at rearward end of frame, Figures 2 and 3 consists of a cylinder 234 closed at one end by cap 230 and gasket 231 and closed and supported at the other end by bracket 232 fastened to frame 40, the bracket 232 and cap 230 being tied together by four studs 233 outside the cylinder. Inside the cylinder is a piston comprising a backing 236, a leather 237, an expander 238, and a washer 239 mounted on piston rod 235 and held to that by cotter-pins 239. The design of the piston is substantially that shown in my co-pending application Serial Number 139,081. A rod 242 engages into piston-rod outside the bracket 232 and extends to trigger 42 later described into which it connects pivotally. A nipple 234' through cap 230 has tube 109 cemented into it, so that air pressed from the tire-contact pump, Fig. 1, is conveyed into the cylinder 234 to press against the piston.

The arrangement of the tire-contact pump and the actuator differs from the means observed at some gasoline vending stations in which a rubber hose lying in the path of vehicles is pressed upon by the road-wheels of the vehicles to transmit air to close an electric relay in the electric-supply circuit to ring a bell. The difference is in the size of the tire-contact cylinder and in the idea of applying the principle of hydraulics to a compressible gas such as air. Using a tubing of a convenient cross-section and a tire-contact pump of given diameter, it was found that the pressure upon a piston having a diameter corresponding to the inside diameter of the tubing would not lift an ounce. (Of course, the veriest fraction of an ounce is enough to close an electric relay.) By using an enlarged chamber for the piston, the air-pressed by the same tire-contact pump through the same size of tubing was found to lift far more. Through a considerable range of piston-sizes, it was found that the lift is proportional to the size of the cylinder and a size was developed to lift 3 pounds, well beyond the needs in setting off a door-operator.

The obtaining of the required power at the actuator end of the tubing is not a matter merely of increasing the size of the hose used in the prior art. Where the hose is of uniform diameter throughout, volume at the actuator end is lost in the compression that occurs within the hose. An appreciable distance is required for practical purposes between the tire-contact and the actuator. Twenty feet from the doorway is about a minimum for placement of the wheel-contact, and twenty feet more are needed within the garage. To transmit air this distance at a required pressure the tubing to the garage must be restricted in diameter in relation to the diameter of the wheel-contact air-pump, so that a relatively high rate of compression is obtained within the tubing, somewhat as the higher voltages in electric wire transmit the more current.

Air-actuator applying to an electric switch

Rod 242 could be applied to throw the lever of an electric switch such as described in reference to Figure 4 of my co-pending application, Serial No. 139,082, or such as may be used with any door-operator driven by electric motor. A variation in application of the "hydraulic" prin-

ciple is shown in Figure 5, appropriate to a shorter distance of actuating movement. A diaphragm 245 of pliant material such as thin rubber is capped on one end of a thick walled rubber tube 244 and cemented air-tight to the outside walls of the tube. Into the other end of the tube a nipple 246 is cemented and into that hose 109 is cemented. The nipple is threaded through a bracket 247 and locked on by nut 248'. Bracket 247 carries also electric switch 243' of which handle 248 is in contact with the diaphragm. The air-pressure from the tire-contact pump causes the diaphragm to bulge out against the handle 248 to throw the latter. This action may close a circuit to a solenoid or close the circuit directly to an electric motor. A spring may be provided to throw off the switch where a solenoid is used, or the drive by the electric motor may throw off the switch when the door reaches the termination of its movement, as will appear in my patent application upon motor-operated doors shortly to be filed.

Belt-cable control of grapnel

In my co-pending application Ser. No. 139,081 and in Patent 2,127,376 an arrow-hook 44 is used by which to engage the closing-weight's cable 102 upon a lug or jaws attached to runner 48; and in my co-pending application Ser. No. 139,082 a pair of clutch-members 210 and 211 in scissors formation engage upon clutch-element 53 for the same purpose. These means are effective so long as gravity by the weight upon the cable is not interferred with. But progress in the use of garages has introduced one or more garbage-cans into the corner in which the weights may be located and placement of these cans is not at all times clear of the weights. So that when the door-closing motive weight in its downward course comes to rest upon an obstruction such as a garbage-can and the movement of runner 48 continues under momentum, the hold upon the member 53 is disengaged. The clutching or grabbing means then falls to the floor of the channel-frame 40 and upon the weight being dropped to the floor of the garage the grabbing means in co-pending application Ser. No. 139,082 may not find its way correctly into brackets 95 and 97; or in co-pending application Ser. No. 139,081 or Patent 2,127,376 may plunge into its fulcrum with such force as to break itself or its fulcrum or the cable 102.

In Figures 2, 2-a, 3, and 3-a of this application the cable 102 shown to run through the grapnel 44, (held to the cable by set-screws, and thus adjustable endwise), and to extend forward to sheave-wheel 86, around that sheave-wheel and rearward to a swivel 104 and a spring 105 that engages by cotter-pin 106' to a shifter 106 which is in place on that part of cable 102 which is on the farther side of the assembly, and is held in place by set-screws, and is adjustable endwise on the cable. The train of these parts with cable 102 forms an endless belt around sheave-wheels 83 and 86 so that, when the grapnel 44 moves forward with runner 48, cable 102 on the grapnel's side moves forward, while cable 102 on the far side moves rearward. Spring 105 has the purpose of maintaining a tension upon cable 102 in its belted strand, so that it holds grapnel 44 at a level that is normal for its lodgement at the lug 53 attached to runner 48. Lug 53 is punched with an orifice 53' shaped as shown in Fig. 4 to afford bearing for grapnel 44 at the sides and bottom, and to admit passage through

of grapnel 44 above the normal level. This orifice in lug 53 prevents the escape of cable 102 at all times. The purpose of swivel 104 is to allow for twisting of cable 102. Cables after being put into use gradually twist to relieve themselves of strains set up in manufacture.

Spring 107 and buffer 108 take the shock to avoid breakage of parts as weight 91 drops to the floor in any irregular escape of grapnel 44 through the orifice 53'. Buffer 108 is formed of two pieces of sheet-metal riveted together and to frame 40 affording a slot 108 (Fig. 3-a) through which cable 102 passes on its way to sheave-wheel 84, which slot confines the cable to bring the spring 107, pressed forward by shifter 106, 15 positively against the buffer. The slot affords an area side to side that admits of the cable 102 taking a non-frictional position within it whichever direction cable 102 may take in going around sheave 84, whether toward the right or left of doorway according to the wall upon which the bracket for motive weights is mounted.

Trigger

Trigger 42 pivots on the threads of a screw 56 which is held in threads of a hole in flange of frame 40 and locked by nut 56'. The trigger consists of an upward extending lever 42' and a leaf 42'' normally horizontal formed to a right angle for threading and for riveting to the lever 42'. Both lever and leaf are threaded for the bearing on screw 56. The top-end of the lever receives rod 242 for actuation of the trigger from the air-actuator, the operational movement of the trigger being rearward with rod 242. The leaf 42'' lies both rearward and forward of pivot 56 so that upon rearward movement of the top of lever 42' the rearward side of leaf moves downward and the forward side upward. Through a hole in the lever 42' the pull-rod 65 is connected so that rearward movement of the lever moves also the tappet 25 (Figs. 2-a and 3-a) rearward for release of the latch 24'. By pull-rod 65 and spring 64, aided by vacuum within cylinder 234, the trigger is returned after actuation to the 45 normal position indicated in Fig. 3.

Pivoted upon and riding with runner 48 is a depressor 46 normally held by spring 46' (Fig. 3) upward in horizontal line against the under side of lug 53. The purpose of this depressor is to transmit to latch 60 the downward movement of the rearward side of trigger leaf 42'', to release latch 60 and runner 50, and to do this only when the runner 48 is rearward on the track adjacent to runner 50. The depressor moves away with runner 48 when that runner is drawn forward in manual operation, leaving runner 50 rearward, so that with the runners in those positions a trigger pull releases latch 24' but not latch 60.

The upward movement of the forward side of trigger-leaf 42'' lifts cable 102 and grapnel 44 so that the grapnel clears its hold on lug 53 in a timed relation to the release of latch 60, and frees runner 48 to move forward under pressure from runner 50 applied to cable 100 by the opening-weight. When the runner 48 is drawn forward in manual operation, leaving runner 50 rearward, grapnel 44 goes with it so that while the runners are in those positions the upward lift of the forward side of trigger-leaf 42'' upon cable 102 has no effect to release the grapnel.

Cushion-setter

In automatic operation of doors the termination of the closing movement is cushioned by the

piston-rod 118 being pulled rearward in cylinder 120, whereupon the piston is left in position to move forward in the cylinder to cushion the termination of the opening movement.

But as noted in text of application Serial Number 139,082, under the caption "Single Air-Cushion Acting Two-Ways," a partial movement of doors by hand fails to position the piston for cushioning if the user releases the doors before moving them into fully open or fully closed position. The purpose of the cushion-setter 111 is to move the piston-rod 118 rearward at the beginning of a manual closing movement, and forward at the beginning of a manual opening movement, so that the piston will be set to cushion any reverse movement incident to the release of the doors in manual operation to permit them to reverse direction.

Setter 111 pivots at 52" on runner 48. It has a horn 113 pressed into it and riveted over. It carries an upper paw 111' which consists of an extension-spring wound to coincide with a screw-thread and screwed into a threaded hole in setter 111 and locked by nut 111''. It carries a lower paw 112' held in the same way, locked by nut 112''. Its upper end normally tends toward bumper 47 under stress of spring 113' (Fig. 3) so that its lower or horizontal end normally tends downward upon grapnel 44 and towards cable 102.

On the rod 115 a washer 114 is held by cotters 114' and 114''. Rod 115 at its forward end, Figures 2-a and 3-a, has a groove 115' turned in it.

If the doors are to be opened by hand the cushion setter 111 will be in the position shown in Figure 3. Its horn 113, resting on the grapnel 44 will hold its upper paw 111' in line for engagement with the washer 114. Upon engagement the resistance by the piston and rod 115 will make the paw 111' rest downward in the corner between the washer and the rod-end 115'. The adjustment of ties 129 at cylinder 120 is such that when air is compressed with a rush, as by the doors moving rapidly toward the end of their opening movement, the compression is quick and adequate to arrest the door movement; but that when air is compressed slowly, as in manual handling of the doors, it escapes without perceptible resistance. Accordingly the paw 111' is enabled, 50 without its having to be unduly rigid, to move the piston forward in manual opening. When the piston comes to a stop at the forward end of cylinder 120, the paw springs upward and over the washer 114 which is circular and may be observed in Figure 4 to have its periphery slanting off towards horizontal at the point where the center line of the rounded and flexible paw contacts it, so that a rearward yield of the paw is translated into an upward yield to escape over the washer. When the setter 111, traveling with runner 48, reaches its fully forward position its horn 113 still is bearing on the grapnel. So that in automatic closing, whether door is released by hand-pressure to overcome the latch 24', or by trigger to release the same latch, the rod 115 will not be engaged to cushion the closing action until the doors approach the end of the closing movement. But if the doors should not have been opened by hand and should have been opened by the release of the opening weight the grapnel 44 would have remained rearward in its position shown in Figure 3, and thus the horn 113 would have settled under stress of spring 113' to rest upon cable 102. In this position paw 111' would have lifted out of the way of washer 114, and

after paw 112' had cleared the same washer, (there being a distance of travel by horn 113 upon the grapnel 44) paw 112' would have been in position to engage into the groove 115''. With both motive-weights then in a lower position the next door-movement must be a manual one in re-setting, at the beginning of which the engagement by paw 112' in groove 115'' moves the piston rearward, setting it for cushioning of any reverse movement of doors occasioned by release of the hand application in re-setting.

Track pocket

In Figure 4 the pocket for the track 45 at the upper end of track-bracket 130 is shown to be 15 open above the track except for a nubbin 130' which reaches out to confine the track. The track is of considerable length so that it may be twisted by hand for convenient insertion or removal. The procedure is first to insert the forward end of the track through the rectangular hole that is punched for it in bracket 131, then to twist the rearward end of the track by hand to press under the nubbin the corner of it that is formed by the track's vertical and horizontal flanges, then to let the horizontal flange slip down along the vertical right-hand side of the pocket—right-hand as seen in Figure 4. Removal of the track is by the reverse of this procedure.

Automatic shut-off of electric current

In my co-pending application Serial No. 139,082 there are shown means for closing an electric circuit to a solenoid which effects the trigger-pull to set off the door-operator. When the car is within the garage, as during the night, it is of value to prevent operation of any door-operator that uses electric current for set-off or motivation.

In any door-operator using radio waves from the car for setting off, it is an economy to have the radio-receiver shut off when the car is within the garage.

In Figures 2, 3, and 4, 250' is an electric switch of conventional character having a handle 250 that opens the circuit when moved forward and closes the circuit when moved rearward. Mounted pivotally on the threads of a screw 252 fastened to a bracket 251 welded to the top of runner 50, is a pendant consisting of a tubing 255 into the lower end of which is pressed a paw 256 of extension-spring material. Above and forward of pivot 252 is a stop 253 for the upper end of tube 255 which prevents the lower end of tube 255 and paw 256 from moving out of vertical in the rearward direction while allowing the lower end and the paw 256 to move freely in the forward direction.

Handle 250 is thrown rearward by shifter 106 on cable 102 when at manual opening of the doors, as to get the car out, grapnel 44 moves forward with runner 48, and shifter 106 moves rearward. The electric circuit thus is closed in readiness for actuation or motivation of the doors. Upon the closing of the doors, shifter 106 moves forward away from handle 250 leaving the switch closed. Upon automatic set-off to open the doors the latch 60 for runner 50 is released while the grapnel 44 remains rearward having escaped through the forward moving orifice 53', as described in reference to trigger 42; and the shifter 106 remains forward. The ensuing forward movement of runners 50 and 48 to open the doors, brings paw 256 forward to throw handle 250 forward and open the circuit. The spring-character of

the paw permits it to ride forward over the handle when the latter stops at its fully thrown position. Both weights now are discharged and the circuit is open. Upon manual closing of the doors the paw 256 rides over handle 250 without effect and falls to vertical rearward of the handle. It is not until the doors again are opened by hand, as to get the car out, that the electric circuit again is closed by the bearing of the shifter 106 against handle 250.

Operation

The operation of each of the novel features herein shown has been treated in the text describing each.

Further recitation of operation would largely duplicate that text and the text appearing in my co-pending application Ser. No. 139,081 and Patent 2,127,376.

I claim:

1. In combination, a garage door manually movable between open and closed positions, energy storing means biasing the door to closed position when opened normally, latch means holding the manually opened door open, an elastic air pump of relatively large volume disposed in a position to be crossed by a vehicle tire passing over the same, an air cylinder of relatively large volume provided with a movable spring retracted piston and connected to the air pump by a relatively small diameter tube so that the air expelled from the pump is transmitted to the cylinder to apply pressure against the face of the piston to stress the retracting spring, and piston actuated means to release the latch means so that the energy storing means closes the door.

2. The combination of claim 1, having energy storing means biasing the door to open position when closed manually, a second latch means holding the manually closed door closed, and piston actuated means to release the second latch means so that the manually closed door opens.

3. The combination such as claimed in claim 1, having a first reciprocable runner movable in unison with the door and cooperating with the first latch means, a second reciprocable runner cooperating with the second latch and movable by the first runner into latched position when the door is closed manually.

4. The combination such as claimed in claim 3, wherein the first energy storing means includes a cable carrying a member normally engageable with the first runner to pull the cable in one direction when the door is opened and pull the door closed when unlatched, and piston actuated means to disconnect the cable carried member and first energy storing means from the first runner when releasing the second latch so that the second runner can actuate the first runner and close the door.

5. In combination, a garage door manually movable between open and closed positions, means to latch the manually opened door in open position, means to condition the door for automatic closing when manually opened, means to latch the manually closed door in closed position, means to condition the door for automatic opening when manually closed, an air pump spaced from the door and from which a substantially volume of air is expelled when the pump is traversed by a vehicle tire, a receiver for the air so expelled, said receiver including a power developing piston of substantial area, and piston actuated devices including means to release whichever of the latch means which is latched so that the corresponding con-

ditioning means actuates the door, and means to disconnect the door closing conditioning means from the door so that the door can be automatically opened.

6. A garage door actuating device, comprising a fixed overhead frame with its front end near the door opening and carrying a runner guide, a front reciprocating runner on the guide and connected to the door to move in unison therewith, a door closing cable connected to the runner, a door closing weight to which one end of the door closing cable is connected to be supported thereby, a front runner latch for holding the door open, a front frame supported pulley about which the weight connected end of the cable passes, a 15 rear frame supported pulley and a second front frame supported pulley about which the cable then passes to form a belt-like loop and place the other end of the cable to the rear of the front pulley, a member secured to the rearwardly passing portion of the cable to the rear of the first named pulley, and a tension spring connecting the said member and the cable end to maintain a taught, belt-like loop about the two pulleys irrespective of closing weight imposed tension. 20

25

7. A garage door actuating device such as claimed in claim 6, wherein the front runner has an extension provided with a cable opening with a larger portion and a smaller portion, the smaller portion being in the normal line of the cable between the pulleys, and the door closing cable carries a stop member normally engaging the front of the extension to lift the door closing weight upon manual opening of the door.
